UNITED STATES PATENT OFFICE.

ARTHUR B. MODINE, OF RACINE, WISCONSIN.

RADIATOR.

Application filed December 30, 1916. Serial No. 139,770.

To all whom it may concern:

Be it known that I, ARTHUR B. MODINE, a citizen of the United States, residing at Racine, in the county of Racine and State 5 of Wisconsin, have invented certain new and useful Improvements in a Radiator, of which the following is a description.

My invention relates to means for controlling the temperature of the cooling fluid 10 for an internal combustion engine or the like.

The object of my invention is to produce a simple, efficient, reliable, light and comparatively cheap device of the kind described, in which the circulating fluid and 15 air are so manipulated that the size and weight of the radiator may be greatly reduced without reducing the capacity of the device.

20 To this end my invention consists in the novel construction, arrangement and combination of parts herein shown and described, and more particularly pointed out in the claims.

25 In the accompanying drawings wherein like or similar reference characters indicate like or corresponding parts:

Fig. 1 is a front elevation of a section of my improved radiator with parts removed 30 and broken away to more clearly show the construction.

Fig. 2, is a section taken substantially on line 2—2 of Fig. 1.

Fig. 3 is a view similar to Fig. 1 but showing a slightly modified form of my device. 35

Fig. 4 is a section taken substantially on line of 4—4 of Fig. 3.

Fig. 5 is a front elevation of a complete 40 radiator.

Fig. 6 is a fragmentary side elevation of another modified form of my device.

Fig. 7 is a section taken substantially on line 7—7 of Fig. 6.

Fig. 8 is a fragmentary plan view of one 45 of the vanes shown in Figs. 6 and 7.

Fig. 9 is a view similar to Figs. 1 and 3 but showing a modified form of vane.

Fig. 10 is an elevation of the vane shown in Fig. 9.

50 Fig. 11 is a view similar to Fig. 1 showing another slightly modified form of my device.

Fig. 12 is a view similar to Fig. 1 showing another modified form of my device.

In the form shown in the drawings my 55 improved radiator comprises a plurality of substantially vertical tubes 1—1 each formed

of copper or other suitable material adapted to readily transmit the heat from the fluid within the tube to the air passing through the radiator between them to control the 60 temperature of the fluid in the tubes.

In the preferred construction each wall of the tube is provided with a series of transverse substantially semi-cylindrical corrugations throughout its length, the corrugations on one side of the tube being spaced intermediate the corrugations upon the opposite side so that the cross section of tube remains approximately uniform throughout 65 its length while the center line of the tube follows a zig-zag course. The projecting margins of the tube however are substantially straight and perpendicular throughout their length.

In the preferred construction the several 70 tubes are sufficiently spaced from each other to receive a spiral vane between them each snugly fitting in the corrugations 2 and 3 in adjacent tubes thus accurately locating the tubes both longitudinally and transversely. 75 The longitudinal position of the tubes are such that the points 5 projecting between the corrugations upon the adjacent tubes will be opposite each other and spaced apart approximately the thickness of a tube. 80

The several plates or vanes 4 each comprise a strip of spirally twisted material adapted to readily transmit and radiate heat and are each soldered, brazed or otherwise hermetically attached to the wall of the tube 85 so as to facilitate the transmission of heat to the vane thereby increasing the available radiating surface of each tube. In the preferred construction the vanes or plates 4 are each twisted or curved so that air passing through the radiator between the tubes and vanes will receive a spiral or whirling motion thus forcing by centrifugal action the cooler and heavier air outward against the radiating surface of the tubes as it 90 passes through the spaces between them and will also contact with the surfaces of the vanes and prevent a layer of partially warmed air enveloping the various heating surfaces. Obviously the coolest air will be 95 thrown against the tube surfaces and the outer portions of the vanes, while the warmer air will seek the central portion of the tubes where the vanes have radiated a considerable portion of their heat, thus actually arranging the air as it passes through the radiator to obtain the greatest possible effi-

ciency in dissipating the heat from the circulating fluid. The tubes 1 of my radiator may be connected at their extremities in the usual or any preferred manner, such for example, as by the usual top and bottom tanks 6 and 7 respectively so that the circulating fluid passes into the tanks and through the tubes in substantially the usual manner.

In the form shown in Figs. 3 and 4 the tubes 8 and 9 are constructed substantially in the manner hereinbefore described and a zig-zag strip 10, preferably corresponding in width to the width of the tubes with which it is associated is positioned between the tubes 8 and 9 and connected thereto by the plates or vanes 11 and 12 respectively. The strip 10 and plates 11 and 12 are preferably connected to each other and to the tubes 8 and 9 by brazing, soldering or other hermetical attachment so as to provide for the greatest possible transmission of heat to the plates and strip to secure the greatest heat dispersing efficiency, and while the dissipation of heat will ordinarily be less in this form of my device than in the form previously described, the construction renders it very desirable under some conditions.

In the form shown in Figs. 9 and 10 the tubes are constructed and arranged substantially as shown in Figs. 1 and 2. The vanes for each pair of tubes however are formed of a single strip 14 corresponding in length to the length of each tube and of approximately the same or a corresponding width. A plurality of lateral slits or openings are formed in the strip 14 each extending from one edge of the strip to a point near the opposite edge, the several slits being spaced to accurately correspond to the spacing of the corrugations upon the tubes and the parts or tongues 15 thus formed are each twisted or formed into a spiral vane substantially as hereinbefore described and the entire strip is positioned between the tubes with the several spiral tongues positioned in the corrugations and hermetically attached thereto as hereinbefore described.

In the form shown in Figs. 6 and 7 the radiator comprises a plurality of suitable tubes 16 arranged in rows both laterally and transversely of the radiator and a series of plates 17 are positioned between the several tubes; each extending through a suitable opening in each of the plates 17 to rigidly maintain the tubes in position. In this form a plurality of sections 18 are severed from the plate 17 along two edges and one end leaving each section attached to the plate at one end only. Each section is then twisted to form a spiral and the several sections are so spaced and positioned as to substantially form a continuous spiral extending transversely of the tubes the entire width of the plate 17 whereby the air passing through the radiator between the tubes will be given

a spiral or whirling motion as hereinbefore described. The operation of this form is not as effective under ordinary circumstances as the forms hereinbefore described but increases the efficiency of this type of radiator materially.

In the form shown in Fig. 8 the spiral 19 corresponding to the spiral 18 hereinbefore described is formed by severing a section from the plate 17 at both ends and both sides up to a point near the center of the section where sufficient material is left unsevered to support the section in position in the plate and both ends of the section are then twisted or formed in a spiral shape; this form being used preferably where it is desired to form a comparatively long spiral with insufficient room to provide two of the spirals as shown in Fig. 7.

In Fig. 11 my spirals are provided substantially as hereinbefore described. The tubes 20 however are bent to form substantially rectangular passages through the radiator with the walls of the passages substantially horizontal and perpendicular while in Fig. 12 my spirals are provided in rectangular passages, the walls of which are inclined at substantially forty-five degrees. The operation however in each case remains substantially the same as hereinbefore described. The whirling motion imparted to the air by the vanes 22 and 23 respectively tends to produce greatly increased efficiency in a radiator.

Having thus described my improvement it is obvious that various immaterial modifications may be made in my device without departing from the spirit of my invention, hence I do not wish to be understood as limiting myself to the exact form or construction shown.

What I claim as new and desire to secure by Letters Patent is:

1. In a radiator construction of the kind described and in combination, a plurality of water tubes suitably spaced from each other to form bounding walls of air spaces therebetween, and a plurality of spaced radiating plates formed to provide a plurality of spirals and arranged with a spiral positioned between the tubes and in contact therewith substantially all along their length for agitating the air passing therebetween.

2. In a radiator construction of the kind described and in combination, a plurality of tubes suitably spaced from each other and a plurality of radiating plates each having formed thereon a plurality of spaced spirals, said plates carried by the tubes, with the several spirals positioned between the tubes and in contact therewith substantially along their entire length and arranged to agitate the air passing therebetween.

3. In a radiator construction of the kind

described and in combination, a plurality of tubes suitably spaced from each other, the walls of each tube being provided with a plurality of semi-cylindrical corrugations 5 providing a plurality of air spaces, and radiating plates constructed to provide a plurality of spirals with a spiral in each space, and arranged to impart a swirling movement to the air passing between the 10 tubes.

4. In a radiator construction of the kind described and in combination, a plurality of tubes suitably spaced from each other, each tube being of zig-zag construction to provide 15 a plurality of substantially semi-cylindrical connected spaces, and a plurality of radiating plates formed with spirals, said spirals arranged in each space whereby a rotary movement is imparted to the 20 air passing through said spaces.

5. In a radiator, the combination with adjacent metallic strips forming complementary parts of a series of air cells, of a metallic sheet arranged between said strips 25 having struck out portions forming spiral deflectors in said air cells.

6. In a radiator, the combination with complementary sections of an air cell, of a sheet held between said sections having 30 portions struck out therefrom to form spiral segments each spiral having its edges in contact along their entire length with the wall of the cell.

7. In a radiator, the combination with a plurality of members forming complementary sides of a series of air cells and adjacent water tubes, of a sheet arranged 35 between said side members extending across said cells with its edges tracing the contour of said cells and being in contact therewith.

8. In a radiator, the combination with a plurality of members forming complementary sides of a series of air cells and adjacent water tubes, of a sheet arranged 40 between said side members extending across said cells, and having spiral portions struck out therefrom, each spiral being in contact with the portions of said members forming 45 said cells.

9. In a radiator, the combination with a plurality of members forming complementary sides of a series of air cells and adjacent water tubes, of a sheet arranged 50 between said side members extending across said cells and having spaced spiral portions struck out therefrom, each spiral being in contact with the wall portions of said members forming said cells.

In testimony whereof, I have hereunto 55 signed my name in the presence of two subscribing witnesses.

ARTHUR B. MODINE.
